UNITED STATES PATENT OFFICE.

CHRISTIAN E. HAY, OF CATALDO, IDAHO.

BED.

1,072,610.

Specification of Letters Patent.

Patented Sept. 9, 1913.

Application filed March 6, 1913. Serial No. 752,454.

To all whom it may concern:

Be it known that I, CHRISTIAN E. HAY, a citizen of the United States, and a resident of Cataldo, in the county of Kootenai and 5 State of Idaho, have invented certain new and useful Improvements in Beds, of which the following is a specification, reference being had to the accompanying drawings.

This invention has relation to certain new 10 and useful improvements in beds, and the object of my invention is to provide a bedstead comprising but three members, a head section, foot section and a mattress supporting section, together with certain novel features 15 for securing the mattress supporting member to the side rails.

With these and other objects in view, the present invention consists in the combination and arrangement of parts as will be 20 hereinafter more fully described and finally pointed out in the appended claim, it being further understood that changes in the specific structure shown and described may be made within the scope of the claim, without 25 departing from the spirit of the invention.

In the accompanying drawings forming a part of this specification and in which like numerals of reference indicate similar parts in the several views: Figure 1, shows a plan 30 view of a bedstead constructed according to my invention. Fig. 2, shows a lengthwise sectional view through Fig. 1. Fig. 3, shows an enlarged fragmentary detail disclosing the arrangement of securing the head cross 35 bar at one end. Fig. 4, shows a section on line 4, 4 of Fig. 3. Fig. 5, is a section on line 5, 5 of Fig. 3.

In my present invention I simplify the construction of a bedstead, in that I employ 40 three distinct members, each capable of expeditious and accurate adjustment in position, the whole providing a secure bed structure, of neat appearance, and capable of being easily assembled and readily han- 45 dled.

In the drawings the numerals 11, 11 indicate the posts of the head section, which give support to the head panel 12. Each head post 11, is provided with a slot arranged to receive the hook members 15, of suitable side rails 10. These hook members are arranged to engage suitable pins 16, shown in Fig. 4, as is usual in bed construction.

55 In my invention I employ two similar side rails 10, 10. Near these foot ends each rail

has two hooks similar to those shown in Fig. 4, to engage suitable pins within the foot posts 13, these posts being connected by means of a suitable panel 14.

The two side rails 10, are permanently secured to the foot and head cross bars supporting the bed springs 25.

The bed springs 25, at the foot end, are secured to an angle bar 24' which has its ends 60 27, turned at right angles and apertured, to receive the securing screws 28. The springs 25 are held to the angle bar 24' by means of the clamp bar 23' this bar being secured by means of suitable rivets 26' as shown in 70 Fig. 1.

The head of the springs 25, is secured to an angle bar 24 being held thereto by means of the clamping bar 23, which is secured to the angle bar 24 by means of the rivets 26. 75 From the foregoing it will be understood that the springs 25 are clamped at opposite ends between two angle bars and two clamping bars.

The clamping bar 23 as shown in Fig. 3 is 80 provided with the outstanding ears 22 projecting beyond the end of the angle bar 24, as shown in Fig. 5.

Secured to the rails 10 near the head end is a supporting bracket comprising the base 85 flange 18, and the upstanding beak hook 19, which forms a socket as shown at 21, in Fig. 4. Extending at right angles from the base flange 18, is the securing flange 17, which has suitable openings arranged to receive the securing screws 17.

In shipping the bedstead from the factory to the point where the bedstead is to be assembled, the springs 25 may be coiled upon one of the angle bars 24 or 24', to make a 95 compact coil. The side rails are packed together while the foot section 14 is packed against the head section 12. When the bedstead is to be set up the operator screws the flanges 27 to the side rail 10. The brackets supporting the head cross bar are fixed to the side rails. In securing the head bar 24, to the side rails, the operator would first secure the side rails 10, to the head and foot sections. The bar 24, is then placed upon 105 the inclined edge 20, of the beak hook 19, and forced downward under pressure so that the ear 22, will ride into the slot or socket 21. After the ears 21, are in place the springs will be taut, and the head cross bar 110 24 cannot be displaced. After the head bar 24 is in position, in order to securely fix the

same to the side rails, I employ the bolts 26 which pass through the openings within the clamping bar 23 through the springs 25 and the bar 24 and the base flange 18 being secured by means of suitable bolts 26. The springs 25 are thus securely fastened to the side rails 10, and can then be easily moved so that I provide a bed including but three sections, a spring section, a head section, and a 10 foot section as described. The clamp bar 23 is secured to the head bar 24, by means of the rivets 26.

A bed constructed according to my invention, is simple and inexpensive and both 15 durable and efficient in operation, and the sections can be assembled or disconnected with ease, accuracy and despatch.

Having thus described my said invention what I claim as new and desire to secure by 20 United States Letters Patent is:

The combination in a bedstead of two side rails, a foot cross bar having its ends se-

cured to said side rails near one end, bed springs secured at one end to said cross bar, a head cross bar having a bolt opening near 25 each end secured to the bedstead opposite end of said bed springs, a clamping bar securing said springs to said last mentioned cross bar having an outstanding ear and a bolt opening near each end, a bracket secured near the remaining end of each side rail having a bolt opening and provided with an upstanding beak hook, said ears arranged to slide over and below said hooks and bolts passing through said bolt openings to secure said cross bar and head bar to said brackets, as and in the manner set forth.

In testimony whereof I affix my signature, in presence of two witnesses.

CHRISTIAN E. HAY.
